UNITED STATES PATENT OFFICE.

ALBERT J. LOEPSINGER, OF EDGEWOOD, RHODE ISLAND, ASSIGNOR TO GENERAL FIRE EXTINGUISHER COMPANY, OF PROVIDENCE, RHODE ISLAND, A CORPORATION OF NEW YORK.

AUTOMATIC SPRINKLER.

1,290,762.

Specification of Letters Patent.

Patented Jan. 7, 1919.

Application filed March 30, 1918. Serial No. 225,747.

To all whom it may concern:

Be it known that I, ALBERT J. LOEPSINGER, citizen of the United States, residing at Edgewood, in the county of Providence and 5 State of Rhode Island, have invented certain new and useful Improvements in Automatic Sprinklers, of which the following is a specification.

My invention relates to automatic sprinklers of the type in which the sprinkler is normally held closed by means of a frangible vessel nearly filled with a liquid and is permitted to open, when sufficiently heated, by the fracturing of the vessel resulting from 15 the expansion of the contained liquid. The object of the invention is to provide a sprinkler of this type in which the vessel when fractured will be instantly and effectively shattered, so that no part of it can 20 remain as an obstruction to interfere with the opening of the sprinkler.

The operation of my sprinkler is based on the fact that the boiling point of a liquid rises as the pressure to which the liquid is 25 subjected increases, and I take advantage of this fact by employing in the frangible vessel a liquid the boiling point of which at atmospheric pressures is lower than the intended operating temperature of the sprinkler. When the sprinkler is heated, as by 30 exposure to a fire, the vapor pressure in the frangible vessel increases as the temperature rises and as the pressure increases the boiling point of the liquid rises, the vapor of 35 the liquid being condensed as the liquid expands until eventually the vessel is first filled and then fractured by the expanding liquid. Before fracture occurs, however, the temperature of the liquid is raised above its 40 boiling point at atmospheric pressures, and the result is that when the vessel is fractured and the internal pressure is thereby relieved the heat stored in the liquid above the amount needed for boiling it at atmospheric 45 pressures expends itself as latent heat of vaporization and instantly converts a portion of the liquid into vapor, the expansive force of which effectively shatters the vessel.

A form of sprinkler in which my invention may be embodied is illustrated in the accompanying drawings, in which the figure shows the sprinkler in vertical section.

The sprinkler illustrated comprises a body portion 2, a yoke 3 screwed at one end 55 into the body portion 2, a resilient valve

seat 4 clamped between the yoke and body portion and having a central perforation, a valve 5 resting on the valve seat 4 and normally closing the perforation therein, and a deflector 6 carried by the free end of 60 the yoke, all of the parts above mentioned being of familiar construction. In addition the sprinkler includes a ring 7, preferably cast integral with the yoke 3, a cap-piece 8 resting on and centered by the valve 5, and 65 a frangible vessel consisting of a glass bulb 9 interposed between the cap-piece 8 and the ring 7 and serving as a strut to hold the valve 5 against its seat. The neck 10 of the bulb projects upward beyond the ring 7 and 70 is received within a space left in the upper end of the yoke 3, whereby it is protected from accidental breakage, and the rounded bottom of the bulb is received within and kept in position by a concavity formed in 75 the top of the cap-piece 8 and conforming to the contour of the bulb, the parts being so proportioned that when they are assembled and the yoke is screwed into the body portion to clamp the valve seat 4 in place 80 the latter is flexed slightly by the valve 5 and held tightly against the valve by its own elasticity.

The bulb may be so prepared that it will be fractured at any desired temperature at 85 which automatic sprinklers are required to operate and any one of a variety of liquids may be used in the bulb, provided that the boiling point of the liquid employed is lower than the temperature at which the sprinkler 90 is designed to operate. In the case of sprinklers intended to operate at the usual temperature of 165° F. the liquid which I prefer to employ is ordinary ether, which has a boiling point of about 95° F. at atmospheric pressures. This boiling point is so low, however, that effective shattering of 95 bulbs containing ether can be obtained at temperatures very much lower than 165° F., so that by using ether in the bulb I am able 100 to produce sprinklers adapted to operate at any desired temperature within a wide range not covered by sprinklers of the fusible-solder type. For sprinklers intended to operate at higher temperatures than 165° 105 F. a liquid having a higher boiling point than ether is preferable, in order that the bulb may not be subjected to excessive internal pressure prior to fracture.

The bulb is prepared by first completely 110

filling it with the liquid and then heating it and its contents to a temperature, determined by trial, which is less than the intended operating temperature but bears a 5 definite relation to it, depending upon the elasticity and co-efficient of thermal expansion of the material of which the bulb is made. This heating causes the liquid to expand and overflow, leaving in the bulb a 10 proper amount of the liquid to fracture it when heated to the intended operating temperature. The neck of the bulb, which preferably has a capillary bore, is then sealed, after slight cooling to free the neck from 15 liquid at the point of sealing, and after this has been done the subsequent cooling of the bulb to normal temperature results in the contraction of the contained liquid, leaving above it an expansion space which 20 contains only the saturated vapor of the liquid at a pressure corresponding to the temperature of the liquid. The bulb is then assembled with the other parts of the 25 sprinkler as already explained.

If the temperature reached by the liquid during the preliminary heating above described is above the boiling point of the liquid the heating should be carried on in a closed vessel at a pressure high enough 30 to prevent actual boiling, which would be likely to expel too much liquid. I have found, however, that there is a sufficient margin between the temperature reached during the preliminary heating and the 35 fracturing temperature of the bulb to permit the employment of a liquid having a boiling point which is at or slightly higher than the temperature of preliminary heating, without materially affecting the operation of the sprinkler in the manner herein-

40

before explained. When such a liquid is used the preliminary heating can be carried on under ordinary atmospheric pressure, which simplifies the operations involved in preparing the bulb.

While my invention is particularly adapted and intended for use in automatic sprinklers, it will be evident that the above-described frangible vessel and its contents, in which the novelty of my invention primarily 50 resides, constitute an article of manufacture which can be used as a thermostatic release in a variety of devices intended to operate at a predetermined temperature.

I claim:

1. An automatic sprinkler comprising, as a means for normally holding the sprinkler closed, a frangible vessel containing a liquid the boiling point of which at atmospheric pressures is lower than the intended operating temperature of the sprinkler, substantially as described.

2. An automatic sprinkler comprising, as a means for normally holding the sprinkler closed, a frangible vessel containing a liquid 60 and an expansion space of such relative volume that the temperature of the liquid when heated sufficiently to fracture the vessel by expansion is higher than its boiling point at atmospheric pressures.

3. An article of manufacture consisting of a frangible vessel containing a liquid and an expansion space of such relative volume that the temperature of the liquid when heated sufficiently to fracture the vessel by 65 expansion is higher than its boiling point at atmospheric pressure.

Signed at Providence, Rhode Island, this 28th day of March, 1918.

ALBERT J. LOEPSINGER.
